UNITED STATES PATENT OFFICE.

HENRY H. CUMMINGS, OF MALDEN, MASSACHUSETTS, ASSIGNOR TO UNION LOCK STITCH COMPANY, OF BOSTON, MASSACHUSETTS, A CORPORATION OF MAINE.

LOCK-STITCH SEWING-MACHINE.

No. 869,981.

Specification of Letters Patent.

Patented Nov. 5, 1907.

Application filed June 17, 1904. Serial No. 212,929.

To all whom it may concern:

Be it known that I, HENRY H. CUMMINGS, a citizen of the United States, residing at Malden, in the county of Middlesex, State of Massachusetts, have invented a 5 certain new and useful Improvement in Lock-Stitch Sewing-Machines, of which the following is a specification, reference being had therein to the accompanying drawings.

In the drawings,—Figure 1 shows in front elevation 10 a portion of a straight-needle lock-stitch sewing machine employing a hooked needle, with an embodiment of the invention applied thereto. Fig. 2 shows the parts of Fig. 1 in elevation from the left-hand side in Fig. 1. Fig. 3 shows the parts of Figs. 1 and 2 in plan, with the 15 work-support, awl-bar, and awl omitted. Fig. 4 is a detail view in elevation looking from the left-hand side, as in Fig. 2, but with some of the parts of Fig. 2 omitted. Fig. 5 is a detail view mainly in vertical section on a plane passing transversely through the center of the 20 shuttle at right angles to the line of feed. Fig. 6 shows the shuttle separately in plan. Fig. 7 is a view similar to Fig. 5 showing a different embodiment of the invention. Fig. 8 is a view similar to Fig. 4 but showing still another embodiment of the invention. Fig. 9 is a view 25 illustrating the application of the invention to a curved-needle lock-stitch sewing machine.

Having reference to the drawings,—A portion of a post or standard forming part of the frame-work of a straight-needle sewing machine is represented at 1, 30 Figs. 1 and 2, and at 2 is represented a work-rest or work-support upon the upper end of the said post or standard 1. 3, in Figs. 1 and 2, is an awl working from above the said work-rest or work-support, and 31 is the awl-bar carrying the said awl. Only a portion of the awl-bar is shown.

4 is an ordinary hooked straight needle working from below the work-rest or work-support, and 41 is the needle-bar carrying the said needle, only a portion of the needle-bar being shown.

40 The awl-bar and needle-bar, in practice, respectively have connected therewith suitable means for reciprocating the same, and respectively are mounted in guides (not shown) as usual, in which they move lengthwise in right lines.

45 5 is a rotary loop-taker having the working position thereof below the work-rest or work-support, the loop-taking point of the said loop-taker being designated 59 in the illustrated embodiment of the invention the loop-taker is a shuttle. The said 50 shuttle is essentially cup-shaped, as shown best by Figs. 5, 6 and 7, it being formed with a large bobbin-chamber which is surrounded by a raised annular rim, and being provided within the said chamber with a bobbin-supporting post 51.

55 52 is a thread-container, herein a bobbin which oc-

cupies the chamber and is mounted therein upon the said post.

53, Figs. 1 and 2, is a shuttle-driver, and 54 is an upright shaft having the said shuttle-driver attached thereto, the said shaft being mounted in bearings in the 60 post or standard 1. In practice, the shaft 54 has connected therewith suitable means for rotating the same, not necessary to be shown. The shuttle 5 is mounted in a shuttle-race comprising opposite side-pieces 6, 6, and a removable section or slide 61 between the said 65 side-pieces, the edges of the portions 6, 6, 61, of the shuttle-race entering a circumferential groove 55 which is formed in the exterior of the shuttle, and the removable 70 of the section 61 providing for the insertion and withdrawal of the shuttle.

As thus far described, the parts operate essentially as usual in hook-needle wax-thread sewing machines. Thus, the awl passes through the stock from one side of the latter to form a hole therein. The needle is passed through the said hole from the opposite side of the stock, 75 and after having had the needle-thread placed within its open eye by the action of the thread-guide (looper) is retracted, drawing a loop of needle-thread through the said hole. The said loop is engaged by the shuttle-point and by the rotation of the shuttle is passed around 80 and over the latter, whereby it is interlocked with the shuttle-thread, being then discharged from the shuttle-point and drawn up to tighten and complete the stitch.

The invention consists in improved means of imparting tension to the shuttle-thread, and holding or locking the same against the pull of the needle-thread in the tightening of the stitch. The said means is adapted to be arranged to act (a) continuously with substantial uniformity in the degree thereof; or (b) continuously and with temporary increase in the degree there- 90 of as the tightening of the stitch approaches completion, in order to hold the shuttle-thread at such time against the pull which is exerted thereon by the needle-thread in setting the stitch; or (c) intermittently, at and about the time of the tightening of the stitch, 95 the shuttle-thread being substantially free from the action of the tension means at other times.

In carrying the invention into effect, I combine with the shuttle a rotatable disk, or the equivalent thereof, which is con-axial with the shuttle, it having a working 100 position in which one radial surface thereof is located immediately adjacent the edge of the rim of the shuttle, and the said surface co-operating with the said edge in compressing the shuttle-thread as the latter issues between the edge and the disk. Preferably, the said 105 disk is con-axial with the loop-taker or shuttle, it may be a separate disk, or it may be one of the heads of the bobbin which is contained within the shuttle. The former construction is shown in Figs. 4 and 5 of the drawings; the latter, in Fig. 7. The separate disk 110

of Figs. 4 and 5 is mounted in working position by means of a central spindle 81, Fig. 5, projecting downward therefrom, which enters the central bore of the tubular post 51 of the shuttle. It is supported vertically by an annular shoulder thereon at the top of the said post, which rests upon the upper end of the post. The peripheral margin of the disk projects over the upper edge of the rim of the shuttle, and is located in close proximity to the said edge. The disk may be 10 free to turn independently with relation to the shuttle, or it may be so engaged with the shuttle as, for instance, by the frictional engagement between spindle 81 and the interior surface of post 51, as to cause it to remain in fixed, or substantially fixed, relation with respect 15 to the shuttle. In Fig. 7, the upper head 57 of the bobbin is made larger in diameter than the lower head 58, and when the bobbin is in place in the chamber or cavity of the shuttle-body the marginal portion or rim of the upper head 57 projects over the upper edge 20 of the rim of the shuttle-body, substantially as in the case of the corresponding portion of the separate disk 8 of Figs. 4 and 5. By setting the disk and shuttle in proper relationship to cause the acting surface of the disk to approach to within the diameter of the shuttle- 25 thread with respect to all portions of the edge of the rim of the shuttle, a continuity of tension will be produced. In a case in which the closeness of approach is uniform around the circuit of the rim of the shuttle the tension of the shuttle-thread will be rendered uniform. By varying the closeness of approach at a given 30 point, as by means of a swell or rise upon the rim of the shuttle, shown at 7 in Figs. 4 to 7, an increase of tension will occur as such point passes and acts upon the portion of shuttle-thread issuing between the disk 35 and shuttle-rim, thereby rendering the tension variable by occasioning a periodical gripping or pinching of the shuttle-thread between the shuttle-rim and the disk. By setting the shuttle-rim and the opposing disk in such relation to each other that the shuttle-thread 40 shall be free from compression except when acted upon by the swell or enlargement of the shuttle-rim, this periodical action alone may be secured, leaving the shuttle-thread substantially free from the tension means at other times. This temporary increase of the tension 45 of the shuttle-thread at the time of the final tightening of the stitch I term the shuttle-thread lock.

The principles which are embodied in the shuttle-thread lock are as follows:—After a loop of needle-thread has been engaged by the shuttle-point, passed 50 around the shuttle by the rotation of the latter, and cast off from the shuttle, and as the tightening of the stitch advances to completion, the shuttle-thread locking surface constituted by the swell or rise aforesaid, passes the portion of shuttle-thread extending over the 55 rim of the shuttle from the interior of the latter toward the stitch-forming point. The said locking surface presses the said portion of the shuttle-thread in the direction of the length of the axis of rotation of the shuttle, firmly against one face of the disk aforesaid, and there- 60 by in passing the shuttle-thread the said locking surface temporarily clamps or grips the latter at a point between the seam and the source of supply within the shuttle. The clamping or gripping is timed so as to withstand the final pull on the needle-thread in setting 65 the stitch. When the locking surface of the shuttle co-

acts with one of the heads of the bobbin, or another disk which is connected with the bobbin to rotate in unison with the latter, the compression or clamping of the shuttle-thread between the said surface and the said bobbin-head, or other disk serves also by arresting 70 the rotation of the bobbin to prevent overrunning thereof.

Preferably, the compressing and clamping action is made yielding in order to obviate tendency to chafing or cutting of the shuttle-thread, as well as to render 75 unnecessary extreme nicety and delicacy in the setting or adjustment of the parts. To this end, in Figs. 4, 5, 7 and 8 a yielding backing for the disk is provided, the said backing consisting of a spring 9 in the form of a bent leaf-spring, which is attached by one end thereof to the 80 under surface of the work-support. The said spring has a downwardly curved portion which makes contact with the upper side of the disk. The tension of the spring is such as to cause the disk to co-act with the surface 7 to clamp the shuttle-thread with sufficient force 85 to insure the proper tightening of the stitch under usual conditions, but the spring yields to avoid crushing, cutting, or chafing of the shuttle-thread between the surface 7 and the under surface of the disk. The tension of the spring may be regulated, as required, by 90 adjustment of the screw 91 which is shown in Fig. 5. The said screw is applied to a threaded hole that is tapped through the work-support, and its lower end makes contact with one end of the spring. In Fig. 8, in order to secure the required yielding action in clamp- 95 ing the shuttle-thread, the swell 56 is shown formed of a spring, which latter is applied to the shuttle-body and curved in its middle portion so as to project above the upper edge thereof. One end of the said spring is fixed to the shuttle-rim, while the other rests freely 100 upon the top of the said rim.

Ordinarily, the shuttle-thread locking action will not be sufficiently pronounced in practice to hold such thread up to the breaking-point of the latter. I do not necessarily limit myself, therefore, to a positive and 105 absolutely unyielding locking of the shuttle-thread.

The invention is equally applicable, either to straight-needle machines, as illustrated by Figs. 1 to 8 of the drawings, or to curved-needle machines, as in Fig. 9. In the latter figure, a work-support is indicated 110 at 111, a curved awl at 112, an oscillating awl-carrier at 121, a curved needle at 113, and an oscillating needle-carrier at 131. At 115 is a rotary shuttle co-operating with the said curved needle in the production of stitches, at 159 the shuttle-point, at 152 the shuttle-driver, at 154 the rotary shaft on which the said shuttle-driver is mounted, and at 156 the shuttle-race. The disk co-operating with the edge of the rim of the shuttle, as explained hereinbefore, is designated 118, and at 117 is the swell or enlargement of the shuttle-rim. An elastic or yielding arm, 119, is attached by means 115 of a screw 120 to the portion 121 of the machine-framing. The free extremity of the said arm projects in front of the shuttle and makes contact with the outer side of disk 118 as in the case of spring 9 of Figs. 1 to 7. The 120 said arm serves to retain the disk in place, and constitutes a backing therefor.

I claim as my invention:—

1. In a lock-stitch sewing machine, the combination with a rotary loop-taker having a source of supply for the 125

- locking thread, of a rotatable disk with a radially-extending face thereof immediately adjacent the edge of the rim of the loop-taker, the said parts being constructed and arranged to cause the locking thread to be compressed 5 intermittently between the said edge and face.
2. In a lock-stitch sewing machine, the combination with a rotary shuttle, of a rotatable disk occupying a working position with a radially extending face thereof immediately adjacent the edge of the rim of the shuttle, 10 the said parts being constructed and arranged to cause the locking thread to be compressed intermittently between the said face and edge as it issues between them.
3. In a lock-stitch sewing machine, the combination with a rotary loop-taker having a source of supply for 15 the locking-thread, of a rotatable disk occupying a working position with a face thereof adjacent the edge of the rim of the loop-taker, the said edge having a clamping portion which acts in the rotation of the loop-taker to compress the locking-thread intermittently as the said 20 thread issues between the said edge and face.
4. In a lock-stitch sewing machine, the combination with a rotary shuttle, of a rotatable disk occupying a working position with a face thereof adjacent the edge of the rim of the shuttle, the said edge having a clamping 25 portion which acts in the rotation of the shuttle to compress the locking-thread intermittently as the said thread issues between the said edge and face.
5. In a lock-stitch sewing machine, in combination, a thread-container, a loop-taker rotating around said thread-container, and a rotatable disk with a radially extending face thereof immediately adjacent the edge of the rim of the loop-taker, the said loop-taker being constructed and arranged to intermittently compress the locking thread 30 between said edge and said face of the disk in the rotation of the loop-taker.
6. In a lock-stitch sewing machine, in combination, a thread-container from which the locking-thread extends toward the stitch-forming point in the machine, and a loop-taker rotating around the said thread-container and 35 provided with thread-compression means acting in the direction of the length of the axis of rotation to intermittently compress the said thread at a point between the thread-container and the stitch-forming point.
7. In a lock-stitch sewing machine, in combination, the 40 rotary shuttle provided with an intermittently acting shuttle-thread compressing surface which by the rotation of the shuttle is carried past the portion of shuttle-thread extending over the rim of the shuttle from the interior of the latter, and a disk which is con-axial with the shuttle and against one face of which the said portion of shuttle-thread is compressed by the said surface as the latter passes, with increase in the tension of the shuttle-thread, to thereby withstand the pull on the needle-thread in setting the stitch.
- 55 8. In a lock-stitch sewing machine, a shuttle-thread lock comprising, essentially, the rotary shuttle provided with a locking surface which by the rotation of the shuttle is carried past the portion of shuttle-thread extending over the rim of the shuttle from the supply within the latter, and an opposing disk which is con-axial with the 60 latter and against one face of which the said portion of shuttle-thread is pinched by the said locking surface as the latter passes, one of the locking members being yielding.
9. In a lock-stitch sewing machine, the combination 65 comprising the rotary shuttle provided with the intermittently acting compressing surface, the opposing disk, con-axial with the shuttle and against which the said compressing surface is caused by the rotation of the shuttle to clamp the shuttle-thread, and the spring acting in 70 connection with the said disk.
10. In a lock-stitch sewing machine, in combination, the rotary shuttle having the rim thereof provided with the swell, and a disk which is con-axial with the shuttle and against one face of which the portion of shuttle-thread extending over the rim of the shuttle from the interior of the latter is pinched by the said swell as the latter passes the said portion of thread, to thereby withstand the pull on the needle-thread in setting the stitch.
11. In a lock-stitch sewing machine, in combination, the 75 rotary shuttle having the bobbin-chamber and having its rim provided with the swell, the bobbin contained in the said chamber and from which the thread passes between the edge of one head of the said bobbin and the rim of the shuttle, and over the latter, and a disk which is con-axial with the shuttle and against one face of which the portion of shuttle-thread passing over the shuttle-rim is pinched by the said swell as the latter passes, to thereby withstand the pull on the needle-thread in setting the 80 stitch.
12. In a lock-stitch sewing machine, in combination, a 85 rotary loop-taker, a rotatable disk adjacent the edge of the rim of the said loop-taker, said parts being constructed and arranged to compress the shuttle thread as the latter travels from a central source of supply between the edge of the rim of the loop-taker and the radially extending face of the disk.
13. In a lock-stitch sewing machine, the combination 90 with a rotary loop-taker having a source of supply for the locking thread, of a rotatable disk with a radially extending face thereof immediately adjacent the edge of the rim of the loop-taker, the said loop-taker being constructed and arranged to cause the locking thread to be compressed intermittently between the said edge and face.
14. In a lock-stitch sewing machine, the combination 95 with a rotary shuttle, of a rotatable disk occupying a working position with a radially extending face thereof immediately adjacent the edge of the rim of the shuttle, the said shuttle being constructed and arranged to cause the locking thread to be compressed intermittently between the said face and edge as it issues between them.

In testimony whereof I affix my signature, in presence of two witnesses.

HENRY H. CUMMINGS.
